INFLATED TOTE BAG

Jerry Brodsky, Des Plaines, Ill., assignor to Crowley
Industries, Inc., Crowley, La.

Filed July 16, 1973, Ser. No. 379,348

Term of patent 14 years

Int. Cl. D9—06

U.S. Cl. D9—249

FIG. 1 is a front perspective view of an inflated tote bag showing my new design;

FIG. 2 is a front elevational view thereof;

FIG. 3 is a bottom plan view taken in the direction of the arrows 3—3 on FIG. 2;

FIG. 4 is an edge view taken in the direction of the arrows 4—4 on FIG. 2;

FIG. 5 is a rear elevational view taken in the direction of the arrows 5—5 on FIG. 4; and

FIG. 6 is a top plan view taken in the direction of the arrows 6—6 on FIG. 5.

I claim:

The ornamental design for an inflated tote bag, as shown and described.
